ATTORNEYS.

UNITED STATES PATENT OFFICE.

BALTZAR E. L. DE MARÉ, OF PHILADELPHIA, PENNSYLVANIA.

HEATING FURNACE.

Application filed November 22, 1924. Serial No. 751,499.

The object of my invention is to provide means for adapting an ordinary hot air, hot water or steam heating furnace, designed especially to burn the larger size coal, to efficiently burn the smaller sized hard coal as well as soft coal. The invention, however, may be adapted to any type of furnace.

My invention involves means for the supply of air both to the coal bed and directly to the combustion chamber above the coal bed to insure the combustion of the combustible gases as they leave the coal bed.

In accordance with my invention there is provided a tube carrying the air from a blower, and adapted to extend upwards through a coal bed. The tube is provided with a circular opening in or adjacent to the grate, which (in addition to the air that may be supplied through the grate) furnishes the oxygen required for the fuel combustion zone. The air from the blower finds its way through the ash bed outwards, while the air from the grate (if any be admitted through the grate) is more apt to follow the walls, the combination resulting in an even distribution of the air for the combustion zone.

A number of small holes are drilled through the wall of the tube, where it passes through the coal bed. These are for the purpose of extending the combustion zone through the center of the coal bed and thus provide at the top of the coal bed the heat necessary to ignite the combustible gas rising from the coal. The oxygen for burning the gas is supplied by air, issuing from a circular orifice in the tube above the fuel bed, at more or less approximately right angles to the gas rising from the coal, thus causing a quick and intimate mixture for the combustion of this gas and also having the effect of directing the resulting flame towards the walls of the combustion chamber and thus providing for a better and more efficient heat transfer to the medium, whether water or air which carries away and distributes the heat from the furnace.

The air from the blower keeps the tube from being overheated, and in doing so, is itself preheated, thus increasing the heating efficiency of the furnace. In order further to protect the tube, where it is exposed to a high degree of temperature, it may also be "calorized" or protected with a fire clay sleeve against damage from being over heated.

A preferred embodiment of the invention is shown in the accompanying drawings, in which—

Fig. 1 is a plan view of a furnace, with the top removed, and equipped with a device embodying my invention. Fig. 2 is a side view, partially in section, of a furnace equipped with a device embodying my invention. Fig. 3 is a sectional view showing a detail of construction.

Referring to the drawings, *a* indicates a furnace provided with a grate 14 having a fuel chamber *c* and an ash pit *d*, and provided with a fuel feed opening *e* having a door *f*. *g* is a door for the ash pit below the door *f* and *h* is a flanged fitting to which a suitable smoke pipe may be connected.

Exterior to the furnace is an air blower 10 adapted to force air through a feed pipe 11 (composed of as many sections as may be convenient), the end of the feed pipe extending upward through the grate and terminating, preferably, at or near what, in practice, would be the level of the ash bed. On the pipe 11 is a perforated sleeve valve 12, which is turnable by hand on the pipe into position to bring its perforations more or less into, or entirely out of, alignment with corresponding perforations in the pipe 11. By this means, air may be introduced, if desired, in regulatable quantities, into the ash pit, which air passes up through the grate 14 in the usual manner. Within the pipe 11 is a hand-operable valve 13, by which the volume of air passing through pipe 11 may be regulated. The volume of air passing through pipe 11 may also be regulated by varying the speed of the blower 10, or by regulating the damper on the blower inlet.

Supported on the pipe 11, by means of brackets 15, is a hood 16, provided with perforations 160. The hood causes air passing upward from the pipe 11 to be diverted laterally adjacent the upper surface of the grate or fuel support 14. The air escapes from the annular passage formed between the top of pipe 11 and the rim of hood 16. Overlying the grate 14 and surrounding the pipe 11 is an imperforate plate 17, which prevents air from blowing ashes 105 downwardly through the grate into the ash pit.

Mounted on the hood 16 is a pipe 18 which is provided with perforations through which air escapes laterally into the fuel bed.

On the upper end of pipe 18 is slidably mounted a sleeve 19, which is held in any adjusted position by means of a set screw 20. Sleeve 19 carries brackets 21, to which is secured a hood 22. Air escapes laterally and obliquely from between the hood and the top of the pipe 18. It is this air which is mainly relied upon to effect combustion of the combustible gases that arise from the fuel bed. When the blower is not operating, sufficient air for slow combustion may be obtained by the natural draft of the furnace inducing air through the inlet opening of the blower, the volume of this air being regulated by the damper shown in the inlet opening.

In the operation of the furnace equipped with a device embodying my invention, it will be noted that air for the combustion of the fuel bed, supported on the grate, is supplied mainly through pipe 11 and it will be understood that, if desirable, in using the finer sizes of coal a solid support for the fuel bed may be provided instead of the usual form of grate illustrated in the drawings.

In operation, air supplied through pipe 11 is in part diverted laterally adjacent the upper surface of the grate by means of the perforations 16, thus providing for combustion of the fuel on the grate. Air passing up through the perforated pipe 18 in part passes out through the perforations causing combustion of the fuel immediately surrounding the pipe. The balance of the air in pipe 18 passes out at the upper end and is diverted downwardly into the fuel bed by the hood 22 causing the gases rising from the fuel bed to burn. The gases rising from

the fuel bed are, as it were, roasted out of the fuel and are caused to burn on the addition of air diverted by hood 22 as a result of ignition by the heat arising from the core of burning fuel about the pipe 18, which also serves to highly heat the air which passes through the pipe 18, which is diverted for admixture with the gases by hood 22.

It will be understood that in describing in detail a specific embodiment of my invention, it is not my intention that my invention shall be limited thereto, since various modifications in detail of structure may be made without departing from the spirit of my invention.

Having now fully described my invention, what I claim and desire to protect by Letters Patent is:

1. In a heating furnace the combination with a grate, an air inlet pipe extending from outside the furnace upward through the grate, a second pipe extending upward through the fuel chamber above the grate, means between said pipes to distribute air above the grate, and means above the second pipe to distribute air above the fuel bed, said second pipe being perforated for the passage of air into the fuel bed.

2. The combination defined in claim 1 characterized by the provision of means in association with the air pipe whereby a regulated amount of air may be supplied therethrough.

In testimony of which invention, I have hereunto set my hand, at Philadelphia, Pennsylvania, on this 23rd day of October, 1924.

BALTZAR E. L. DE MARÉ.
